US00D977797S

(12) **United States Design Patent** (10) **Patent No.:** **US D977,797 S**
(45) **Date of Patent:** **** Feb. 14, 2023**

(54) SHOE	2,937,462 A *	5/1960	Hack	A43B 13/223
(71) Applicant: Converse Inc. , Boston, MA (US)	36/149			
(72) Inventor: Alyssa Makere , Boston, MA (US)	2,941,316 A *	6/1960	Hack	A43B 13/223
(73) Assignee: Converse Inc. , Boston, MA (US)	36/32 R			
(**) Term: 15 Years	2,941,317 A *	6/1960	Hack	A43B 13/223
(21) Appl. No.: 29/761,498	36/35 R			
(22) Filed: Dec. 9, 2020	D189,839 S	3/1961	Nakashima

CLAIM

The ornamental design for a shoe, as shown and described.

DESCRIPTION

FIG. 1 is a front perspective view of a shoe showing my new design;

FIG. 2 is a side view thereof;

FIG. 3 is a front view thereof;

FIG. 4 is an opposite side view thereof;

FIG. 5 is an opposite side front perspective view thereof;

FIG. 6 is a bottom front perspective view thereof;

FIG. 7 is a bottom view thereof; and,

FIG. 8 is a bottom rear perspective view thereof.

The broken lines immediately adjacent to the rear ends of the shaded area define the bounds of the claimed design and form no part thereof. The broken lines depicting the remainder of the shoe form no part of the claimed design.

FIG. 3

FIG. 6

FIG. 7

FIG. 8
